UNITED STATES PATENT OFFICE.

JOSEPH FRANCIS ALEXANDER AND WILLIAM GRAHAM ALEXANDER, OF SEATTLE,
WASHINGTON.

CASTING DEVICE FOR DENTAL PURPOSES.

1,038,063.

Specification of Letters Patent. Patented Sept. 10, 1912.

Application filed March 3, 1908. Serial No. 419,043.

To all whom it may concern:

Be it known that we, JOSEPH FRANCIS ALEXANDER and WILLIAM GRAHAM ALEXANDER, citizens of the United States, residing 5 at Seattle, in the county of King and State of Washington, have invented a new and useful Casting Device for Dental Purposes, of which the following is a clear and concise specification.

10 Our invention relates to casting devices in which a paraffin or wax pattern is surrounded by a porous cement investment contained within a suitable casting flask and is advantageously used for dental purposes. 15 We do not wish to be limited to this use however, as we may desire to employ our invention for other casting purposes.

The objects of our invention are, to provide a suitable flask for casting purposes 20 with a means for applying a partial vacuum to draw the metal into said flask; to provide a porous, fusible or combustible partition between the investment and the air pump connection. We accomplish these as well 25 as minor objects by the construction now preferred by us and illustrated in the accompanying drawings in which—

Figure 1 is a perspective view of our device; Fig. 2 is a section through the center 30 of the flask; Figs. 3, 4 and 5 are detailed views of the investment supporting means; Fig. 6 is a section through the center of the hood of our device; Fig. 7 is a perspective view of the cap to the hood of our device.

35 Similar reference numerals refer to similar parts throughout the several views of our device as illustrated in the accompanying drawings.

We have provided a flask 1 having a suitable investment of investment compound, 40 cement, sand, or other material 2 used for casting and adapted to surround the mold 3 which in dental practice is formed by melting the pattern or inlay which is of readily fused or melted material. Thus it 45 is possible by forming a gate 4 to melt and remove the pattern therethrough by heating the flask 1 and cement 2 contained therein. The metal which may be deposited in the 50 recess 5 provided at the end of said gate 4 is then reduced to a molten condition; and to insure the mold 3 being filled with metal we have provided a suitable connection 6 55 communicating with any form of air pump 7 thus inducing the metal to be drawn to-

ward said connection 6 when a partial vacuum is obtained in said air pump 7.

In Fig. 1 we have illustrated our device in its complete form with the flask stationary and provided with a heating means, the air pump 7 being secured to the panel 31 by means of the straps 32 adapted to clamp said air pump 7 to said panel. We have provided a bracket 33 adapted to support a hood 34 and a cap 35 to said hood in co-action with the pipe 36 connected to said air pump 7 by means of the T 37 and nipple 38. Said T 37 is also provided with a cock 39 adapted to relieve the partial vacuum in the pipes and in the pump cylinder of our device. The hood 34 and cap 35 are of the general shape of an inverted cup. The lower portion of the cup or hood portion 34 is disposed substantially annularly around the flask of our device and when the cap of said hood is in place the heat of the burner is maintained constant around said flask thus overcoming drafts which would tend to carry the heat of the burner which is small to one side or the other of said flask instead of spreading flames on all sides. By this means a thermal efficiency of the burner is increased. The flask is supported by the pipe 36 which is secured to the air pump of our device, thus it will be seen as above 85 stated that as the lower edge of the hood 34 rests on the bracket 33, said bracket providing a support at substantially two bearing points, that the pipe 36 forms the third 90 support. The flask 1 we have shown as being rigidly connected to said pipe 36 and permanently held over a Bunsen burner 40 which is provided with an air regulator 41 and hose 42 adapted to supply gas thereto. Said flask 1 by this construction is necessarily provided with a combustible or porous disk 43 which supports the cement or investment 2 which is deposited there in said flask in a liquid state until set. When the heat is applied to said flask said combustible 95 disk 43 will be burned and will permit the suction on the pump to act upon the mold 3 thereby aiding the flow of metal in the mold and insuring a perfect casting. We do not wish to be limited to a combustible 100 disk 43, however, and have shown a disk composed of porous cement 44 reinforced by a wire screen 45. The disk 43 when made of porous material serves substantially the same purpose as the combustible disk, ex- 105 110

cept that a disk made of combustible material has to be renewed each time a heat is taken off. The porous cement with a wire reinforcement being substantially fire proof is slightly more expensive from the point of manufacture but is preferred by some operators. To maintain a partial vacuum on our device without holding the handle 6' we have provided a collar 10 46 and thumb screw 47 thus forming a set collar to clamp on the piston rod 48 and acting against the end piece 49 of said air pump 7.

It is obvious that numerous methods may 15 be employed to provide a partial vacuum in said connection 6, and we do not wish to be limited to the specific construction as herein set forth and illustrated in the accompanying drawings.

20 Having thus described our invention what we claim as new and desire to secure by Letters Patent of the United States is:

1. In a dental casting device, an air pump and a flask rigidly connected thereto and a 25 detachable supporting means provided at the base of said flask preventing investment compound in said flask from entering said air pump connection and adapted to permit the circulation of air into said air pump 30 connection.

2. In a dental casting device, a flask supporting investment material, an air pump connected at the base of said flask and a removable investment supporting means 35 whereby said investment is held in said flask and prevented from gravitating into the air pump connection when in a plastic state.

3. In a dental casting device, a flask and a mold of porous investment material supported in said flask, an air pump connected 40 to the base of said flask and means preventing said investment when in a plastic condition from gravitating into the connection to said air pump.

45 4. In a casting-device, a flask, a heating means thereunder, an air pump connected to said flask, means whereby investment material is prevented from gravitating into said connection and whereby said flask may be 50 fixed to said connection during the process of filling said flask with said investment material and during the process of casting.

5. In a casting device, a flask, an air pump connection at the base of said flask, a heating means and an investment supporting device adapted to support said investment ma-

terial when in a plastic state whereby air may be admitted through the investment and said supporting device to obviate the handling of said flask and permitting said flask 60 to be permanently connected to said air pump.

6. In a casting device, an air pump, a flask secured thereto, whereby said pump and flask are connected during the process of 65 melting and casting and a removable supporting member provided between said flask and said pump.

7. In a casting device, a mold support provided with a removable perforated base, 70 a porous mold mounted thereon, an air chamber formed on said base adjacent said perforations, means connected with said chamber for maintaining a vacuum, and means for suddenly reducing said vacuum, the influx of air into said vacuum maintaining means forcing the metal into said mold.

8. In a casting device, a flask and an air pump connected thereto, a hood and cap, and means for removably supporting said hood 80 in fixed relation with said flask whereby said flask may be filled when connected to said pump, and means for supporting the investment material in said flask when in a plastic state whereby said investment material is 85 prevented from gravitating into said connection.

9. In a casting device, a flask and an air pump connected thereto, a hood and cap, and means for removably supporting said hood 90 in fixed relation with said flask whereby said flask may be filled when connected to said pump, means for supporting the investment material in said flask when in a plastic state whereby said investment material is prevent- 95 ed from gravitating into said connection, a heating means for said flask whereby metal may be melted, said air pump being connected to said flask while said metal is being melted forcing said metal into said flask by 100 the air passing through said investment material and the support therefor when said pump is operated.

In testimony whereof we have signed our names to this specification in the presence of 105 two subscribing witnesses.

JOSEPH FRANCIS ALEXANDER.
WILLIAM GRAHAM ALEXANDER.
